UNITED STATES PATENT OFFICE

FRANK WILLIAM EDWARDS, OF CHICAGO, ILLINOIS, AND NORMAN M. BARKER, OF LAKEWOOD, OHIO, ASSIGNEES, BY MESNE ASSIGNMENTS, TO THE OHIO INJECTOR COMPANY OF ILLINOIS, OF CHICAGO, ILLINOIS, A CORPORATION OF ILLINOIS

RAIL AND FLANGE OILER.

Application filed January 25, 1929. Serial No. 335,069.

This invention relates to a rail and flange oiler or lubricator for the purpose of automatically supplying lubricant to the inner side of the head of the outer rail upon curves in a railway track, the lubricant preferably being applied to the flange of a wheel of one of the vehicles or units of a train, and such wheel running upon the outer rail of the curve and transferring the lubricant from its flange to the inner side of the rail head.

We are aware that apparatus has been heretofore devised for performing this function, but in such apparatus with which we are familiar certain faults in construction and operation are present which result in impracticability from a manufacturing and marketing standpoint or in inefficient operation, or both.

Any such apparatus, to be serviceable, must be designed to supply lubricant to either the right-hand or left-hand rail of a railway track depending upon which rail happens to be upon the outside of the curve, and hence two lubricant feeds, one to a wheel on the right-hand rail and the other to a wheel on the left-hand rail, must be provided, and means must be associated with such feeds for admitting oil to them only at proper times. Lubricant must feed either to right or left, but not both, when the train travels a curve, but not when standing upon the curve, and no lubricant should be fed when the train is running or standing upon straight track.

Certain phenomena incident to the operation of trains are utilized in causing our device to function properly, and other phenomena are guarded against to prevent improper functioning. For example, the banking or elevation of the outside rail of a track upon curves, and the vibration of the locomotive or other railway vehicle upon which the oiler is mounted, are utilized to cause the oiler to function; whereas the swaying of the locomotive due to speed or rough track, and sudden lurching of the locomotive due to low spots or faults in the track are so guarded against that they do not cause improper functioning of the device.

The object of our invention is to provide a rail and flange oiler of the type referred to

wherein all of the faults of such devices now known to us are eliminated and whereby many advantages are obtained, as will hereinafter appear.

The invention consists, broadly, in a rail and flange oiler, including a lubricant reservoir adapted to be so fixedly mounted upon a railway vehicle, preferably the locomotive, as to partake of all motions made by the vehicle during its travel, this reservoir being provided with valve-controlled feed passages connected by means of suitable conduits with delivery nozzles arranged adjacent to the parts to be lubricated. The valves of the passages are controlled by a single gravity responsive member, preferably in the form of a pendulum, which remains in a substantially vertical position at all times and with respect to which the reservoir tilts due to tilting of the locomotive upon banked curves of the railway, this relative movement between the pendulum and reservoir causing the pendulum to actuate one or the other, but not both, of the passage-controlling valves. And the invention consists, further, in various details of construction and arrangements of parts whereby most efficient operation is obtained, as we will proceed now to explain and finally claim.

In the accompanying drawings illustrating the invention, in the several figures of which like parts are similarly designated, Figure 1 is a vertical, sectional elevation of the lubricant reservoir and associated parts, which we will call the lubricator proper, taken substantially on the line 1—1 of Fig. 4. Fig. 2 is a vertical section of these parts taken on line 2—2 of Fig. 4. Fig. 3 is a vertical section similar to Fig. 2 but taken on line 3—3 of Fig. 4. Fig. 4 is a top plan view of the reservoir and parts associated therewith. Fig. 5 is a fragmentary elevation of the lubricator proper, showing the application thereto of a pivoted indicator and scale for showing the inclination at which the device is adjusted to operate. Fig. 6 is an enlarged fragmentary detail of the scale of such indicator. Fig. 7 is a schematic side elevation of a typical installation of our device in connection with a locomotive and tender, por-

- tions only of the latter being shown in broken lines. Fig. 8 is a schematic plan view of some of the parts shown in Fig. 7, and in addition showing an arrangement of pressure gages 5 whereby a check upon the operation of the apparatus may be had. Fig. 9 is a rear view of the lubricant delivery member and its mounting bracket. Figs. 10 and 11 are, respectively, a bracket-contacting face view, 10 and a side view of the delivery member and a portion of the universally pointed or flexible conduit connected therewith. Fig. 12 is a sectional elevation of a modified form of the lubricator proper.
- 15 The lubricator proper comprises a lubricant reservoir A formed, preferably, of a cylindrical shell 1 having applied at its upper and lower ends, respectively, in any appropriate fluid-tight manner, as by screw- 20 threads, a top flange 2 and a bottom cap 3. Applied to the top flange 2, fluid-tight, as by studs 4 and nuts 5, and, if desired, a suitable interposed packing washer (not shown) is a top cap 6 provided with similar lubricant 25 passages including pockets 7, 7' and 8, 8', all of which are closed by similar caps 9. Communication between the pockets 7 and 8, and 7' and 8' is afforded by ducts 10, only one of which is shown (Fig. 2). The pockets 7 30 and 7' are in communication with the interior of the reservoir A by way of valve seat members 11 screwthreaded through the cap and providing openings between the lubricant passages and the reservoir. Pivoted 35 intermediate the members 11 preferably on ears 12 formed on the cap 6, and provided with a radial ball-bearing 13, is a gravity-responsive member or pendulum 14, weighted at its lower end, as indicated at 15, and carrying adjacent to its pivot a head or valve- 40 actuating means 16 in which are spring-pressed valve members 17 adapted to normally seat on both seat members 11 when the pendulum is in a position normal to the 45 cap 6. The valve members 17 are of substantially the type disclosed in the co-pending application of Frank W. Edwards for High pressure self-grinding valves, filed July 2, 1926, Serial No. 120,173, now Patent No. 50 1,890,248, granted December 6, 1932, and have the same characteristics and attributes of seating efficiency, self-adjustment and seat-conforming wear.
- At the lower end of the pendulum, and 55 preferably associated with the weight 15 thereof is a pair of dash-pot cylinders 18 provided with fluid ducts 19 and cooperating with pistons 20 preferably formed as an integral structure in which is a bushed bore 60 21 arranged for vertical sliding movement in contact with a ball-headed positioning member 22 fixed to the bottom cap 3. This member 22, obviously, prevents any lateral movement of the piston structure and hence, 65 as the reservoir tilts relatively to the pendu-

lum, the cylinders 18 will move relatively to their pistons 20, in a manner and for a purpose hereinafter more particularly described.

A T connection 23, connected with a steam pipe 24 (see Fig. 8) preferably in communication with the locomotive boiler, supplies steam through branch pipes 25, 25', to valve pockets 26, 26' in communication through similar passages 27, (only one of which is shown, Fig. 2) manually controlled by similar needle valves 28, with the pockets 8, 8'. In communication with the passages 27 are right and left-hand lubricant delivery pipes 29, 29', respectively, which pass downwardly through the reservoir and through the body of lubricant therein, and out of the bottom cap 3 where they are provided with suitable packing glands 30, and are connected by means of valved or choke elbows 31 with the right and left-hand delivery conduits 32, 32', respectively, to be described more in detail later.

By this arrangement it will be seen that any lubricant supplied to the passages 27, 90 through the openings formed by the members 11, will be picked up by the steam which, as a pressure vehicle therefor, conducts the lubricant through the delivery pipes 29, 29' and conduits 32, 32'. At the same time, the 95 steam, which is constantly flowing through these pipes 29, 29', will heat the body of lubricant in the reservoir and maintain it in that condition of fluidity necessary for proper functioning of the apparatus.

It will be noted here that the reservoir A is provided with a heat-insulating jacket comprising a metallic shell 33 and packing 34 of some appropriate material, such as asbestos, whereby heat communicated to the body of lubricant by the steam, as just explained, will not be radiated therefrom through the walls of the reservoir, and a surrounding cold atmosphere will not materially affect the lubricant.

The T connection 23 also communicates through a valve 35, preferably a ball valve, with a condensation pipe 36 leading to the bottom portion of the reservoir whereby water of condensation may be supplied to 115 the reservoir to cause the lubricator to operate upon the hydrostatic or condensation-displacement principle. The condensation pipe 36 is provided at its outlet end with a check-valve 37 (see Fig. 3) whereby reverse 120 flow of oil or water into the pipe is prevented.

Choke plugs *a* are used in the T connection 23 to control the flow of steam to the pipes 25, 25' and 36.

The pockets 8, 8' are provided with automatic vibration- or motion-responsive valves 38 of substantially the type disclosed in the patent of Frank W. Edwards No. 1,433,449, granted October 24, 1922, whereby lubricant, 125

when fed to these pockets from the reservoir, will be permitted to enter the passages 27 only when the vehicle (the locomotive) on which the device is mounted is in motion and 5 the balls 39 of the valves are unseated by the vibration or movement caused by or incident to such motion. In this connection it will be noted (see Fig. 2) that the seat-piece 40 provided for the ball 39 of the valve has a circumferential flange 41 which limits movement of the ball, and also that the seat on which the ball rests is of sloping or radially inclined contour toward the orifice 42 in its center. The angle of inclination of this seat 10 is such that the banking of any railway curve will be compensated for when the vehicle stops on such curve, and, therefore, in spite of the angle or tilt assumed by the lubricator due to the angle of banking of the 15 curve, the ball will roll to its seat over the orifice and the feed of lubricant past the valve will be arrested.

As hereinbefore stated, the members 11 are screw-threaded through the top cap 6, and it 20 will be obvious that adjustment of these members toward and away from the valve members 17 will diminish or increase, respectively, the sensitiveness of the operation of the lubricator. For example, the angle of 25 inclination of the lubricator proper, caused by the banking or elevation of the outside rail on a curve, is the medium by which either of the valve members 17 is moved away from its seat member 11 and, therefore, the members 11 may be so adjusted that the valve members 17 will unseat upon inclination of the lubricator to any predetermined angle corresponding to the banking of a curve of a certain radius to accommodate 30 trains travelling at a certain predetermined maximum speed. Obviously, when the valves are adjusted to open at a certain angle of inclination or tilt of the lubricator, they will open upon occurrence of greater angles of 35 inclination, but not of angles of less inclination, and thus the apparatus may be adjusted to deliver lubricant when running over curves having a certain predetermined elevation of outside rail or an elevation in excess of such predetermined elevation.

To facilitate this adjustment of the seat member 11, we may, if desired, provide our device with the indicator illustrated in Figs. 5 and 6. This device comprises a pivoted arm 43, the pivot 43' of which is in axial alignment with the pivot of the pendulum 14, and this arm is provided with a pointer 44 which registers with a scale 45 graduated in inches and fractions of inches corresponding to the various standard elevations for the outside rail on curves of various radii. The arm 43 is preferably formed at its free end with a slotted enlargement 46 the slot of which embraces a screw 47 fixed to the member which carries the scale 45, and with this

screw cooperates a binding nut 48 whereby the arm may be fixed in any desired position. The enlargement 46 not only provides the slot mentioned, but furnishes sufficient weight at the free end of the arm 43 to cause 70 same to function with the stability of an ordinary pendulum.

In using this device to facilitate the adjustment of the seat member 11, we mount the lubricator proper in such a manner that it may be tilted at will to any desired inclination, and then release the nut 48 so that the arm 43 may swing freely about its pivot 43'. Then, knowing the minimum elevation 75 of the outer rail of curves of track over which the locomotive to carry the device is to operate, which we will say is $1\frac{1}{2}$ inches, we tilt the lubricator until the pointer 44 points to the graduation $1\frac{1}{2}$ at the right, say, of scale 80 45. The seat member 11 at the left of the lubricator is then screwed down until it seats upon its respective valve member 17 and is then backed off slightly to unseat it. The lubricator is then tilted until the pointer 44 registers with graduation $1\frac{1}{2}$ at the left of 85 the scale 45 and the seat member at the right of the lubricator is similarly adjusted. With such an adjustment of the seat members, it will be apparent that the valves controlling 90 flow of lubricant from the reservoir will 95 operate at inclinations caused by outer rail elevations of $1\frac{1}{2}$ inches and over, but not at less inclinations.

Referring to Figs. 1 and 2, it will be seen that the adjustment of the seat members 11 100 may be securely maintained by means of jamb nuts 49 and 50, the nuts 49 being formed with conical protuberances and the nuts 50 formed with complementary conical recesses whereby, when the nuts are forced into engagement, the protuberances will be forced 105 into fixed locking engagement with the screw-threads of the members 11.

The reservoir A is filled with lubricant through a filling opening 51 formed in the top cap 6 and provided with a closure plug 52, and may be drained by means of a cock 53 in the bottom cap 3, this cock, in the form shown, carrying the positioning member 22 for the piston structure 20, 20.

If desired, the filling opening 51 may be provided with a strainer (not shown) of any suitable and approved form.

Referring, now, to Figs. 7 and 8, wherein the complete assembly of the apparatus of our invention is schematically illustrated, it will be seen that the lubricator proper is preferably mounted beneath the floor or deck (not shown) of the locomotive cab by securing it to some appropriate part of the locomotive frame or to a suitable bracket (not shown) in such position that the axis or pivot of the pendulum 14 is in alignment with or parallel to the longitudinal axis of the locomotive. In this mode of association of lubri- 120 125 130

cator and carrying vehicle (locomotive), it will be apparent that the pendulum is influenced only by transverse tilting of the vehicle.

5. For the best practical results, it is desirable that the lubricant be applied to the flanges of the wheels of a truck which is in the rear of all driving wheels, including the locomotive drive-wheels and the wheels 10 of any boosters which may be employed. Some locomotive tenders are provided with boosters on their rear trucks, but they are the exception rather than the rule, and for purposes of illustration we have shown the 15 common type of tender which has no booster applied to it.

Moreover, when the wheels of a locomotive, tender, or other unit of a train are rounding a curve in the track, it is the leading wheels 20 of the front truck thereof that do the guiding and are in direct and continuous contact with the outside rail of such curve, and it is preferable, therefore, that the lubricant be delivered to the flanges of such wheels of the 25 front truck no matter upon what unit of the train such truck may be.

The conduits 32, 32', hereinbefore referred to, are made flexible by being formed in a plurality of sections articulated by means of 20 universal joints, preferably ball-and-socket connections 54, so as to accommodate the conduits to relative movement between the two vehicles carrying the lubricator proper (the locomotive) and the delivery members (the tender) respectively. If desired, the conduits may be suitably flexibly supported at appropriate intervals by means of chains, cables or the like, as indicated at 54'.

These delivery members (see particularly 40 Figs. 9, 10 and 11) comprise, preferably in an integral casting, a body portion 55 formed with offstanding lugs or ears 56 providing a means whereby the members may be attached, preferably by bolts and nuts 57, to brackets 58 suitably carried by the side frames of the front tender truck or other appropriate supports. The body portion 55 is provided adjacent to its lower end with a delivery nozzle 59 so angularly arranged relatively to the 45 body portion 55 and lugs 56 carried thereby that when the brackets 58 are properly adjusted and the lugs 56 bolted thereto the nozzles will be located in the desired proximity and angular relation to the front wheels of 50 the tender truck to project lubricant upon the flanges of such wheels as required for proper operation of the device. The upper end of the body portion 55 is provided with an offstanding portion 60 formed to provide 55 one member, preferably the socket member, of a universal coupling or ball-and-socket connection 61 to which the articulated delivery conduit is attached. As will be apparent from an inspection of Figs. 7, 8, 9 and 11, the portion 60 is sufficiently long to extend through

an opening 62 in its bearing bracket 58 so that the body portion 55 and nozzle 59 may be on one side thereof and the ball-and-socket connection 61 on the other side.

In order to provide the operator or engineer with visible means for observing the functioning or non-functioning of the device, we may mount in the locomotive cab, on an instrument board or other appropriate support, three pressure gages 62, 63 and 64. The 70 gage 62 is connected by a pipe 62' with the reservoir proper by way of an opening 65 (see Figs. 1, 2 and 4), and the gages 63 and 64 are connected by pipes 63' and 64' with the pockets 7 and 7', respectively, through the 75 caps 9 thereof (Fig. 8). The gage 62 will always indicate pressure so long as the steam feeds water of condensation to the reservoir, but the gages 63 and 64 will show pressure only when either the right-hand or left-hand 80 valve member 17, respectively, is unseated. Thus, when the operator observes that only the gage 62 indicates pressure, he will know that both feeds are closed, but when either feed is open its respective gage 63 or 64 will 85 indicate a balance of pressure with gage 62.

In Fig. 12 we have shown a modification in which we provide for sight feeds 66, 66' arranged at the sides of the reservoir A, and in place of the delivery pipes 29, 29', which extend directly through the reservoir from top to bottom, we provide pipes 67, 67', which are inclosed within the reservoir for an extent sufficient to provide the requisite heating effect. These pipes 67, 67' are fitted at their ends with unions with which pipes 68, 68' leading from the sight feeds 66, 66' and the conduits 32, 32' are connected.

The sight feed members 66, 66' are of the type disclosed in the patent of Frank W. Edwards, No. 1,433,449, previously referred to and, in addition to the sight feed pockets and sight glasses, include automatic ball valves 69, 69' and manually controlled needle valves 70, 70' which function the same as and supplement the ball valves 38 and feed valves 28, respectively, hereinbefore referred to.

In this modified embodiment of the invention we have omitted the ball bearing for the pendulum 14 and have substituted for the dash-pot arrangement a guide block 71 which cooperates with a groove 72 in the bottom of the pendulum weight 73 to prevent movement thereof other than pivotal movement, but omitting the vibration or shock absorbing feature of the dash-pot arrangement.

The operation of our rail and flange oiler is, briefly, as follows:—The ball valve 35 is closed, and the reservoir A is filled, through the filling opening 51, with a heavy oil, preferably heavy asphaltum oil. Then, with valve 35 open, water of condensation formed in pipe 36, and entering the reservoir therethrough, will displace the oil upwardly in the reservoir under a pressure sufficient to main- 130

tain it always in the zone of action of valves 11-17 and force it through the passages leading to the delivery pipes 29, 29' should either of the valve members 17 be unseated. The lubricator is now in condition to operate.

With the locomotive on straight track the pendulum 14 and the reservoir A are both in a vertical position and the valve members 17 are both seated against the seat members 11 so that no lubricant can pass them. When the locomotive reaches a curve and meets the elevation of the outer rail, both the locomotive and the reservoir A will be tilted from the vertical, but the pendulum will remain in the vertical position. This is equivalent to swinging the pendulum to one side within the reservoir, and the valve member 17 on the high side is unseated and permits oil to flow through member 11 into pocket 7 or 7' and through the communicating duct 10 into pocket 8 or 8'. As the locomotive is in motion, the vibration caused thereby will keep the balls 39 unseated and the lubricant will flow through orifice 42 into passage 27 and thence past valve 28 where it is picked up by the steam entering through pipe 25 or 25' and conducted through pipe 29 or 29' and conduit 32 or 32' to one or the other of the delivery nozzles 59 (depending upon which one is adjacent to the wheel travelling on the elevated rail) from which it is projected upon the flange of the adjacent wheel and by this flange applied to the inner side of the head of the outer rail.

Should the locomotive stop upon a curve, the ball valves 38 will close and the feed, though open at one of the members 11, will be arrested until the locomotive is again in motion.

The pendulum 14, being fitted with a ball-bearing pivot 13, is very sensitive to any sidewise motion of the locomotive but, due to the arrangement of dash-pot cylinders 18 and pistons 20, a sustained tilt, such as is produced when the locomotive travels a curve, is necessary to cause the pendulum to so function as to open one of the valves 11-17. A sudden lurch of the locomotive due to a low spot in the track, or swaying due to speed or rough track, will not be sufficiently sustained in one direction to cause the pendulum to operate against the influence of the dash-pot arrangement.

The action of this dash-pot arrangement would seem to be obvious but, in the interest of clearness, it may be said that, as the pendulum and reservoir move relatively, the fluid surrounding the cylinders 18, water or oil as the case may be, will be slowly drawn into and expelled from the cylinders through the ducts 19, thus making the response of the pendulum somewhat sluggish.

It will be understood that the oil is deposited upon the flanges in such quantities that the flange of each wheel of every car or

unit of the train will be coated with oil as the wheel flanges come in contact with the inside of the head of the rail. After a train has travelled several curves, the flange of every wheel in the train will be heavily coated with the heavy asphaltum oil and each flange will be protected against wear and friction, as will also the rails.

It is to be noted that heavy asphaltum oil has been found to be most suitable for our purpose. It will not clog feed ports, nor spread from the flanges to the treads of the wheels, but will cling to the flanges and to the inner side of the head of the rail under all weather conditions.

From the foregoing description, it will be seen that we provide, by our invention, a rail and flange oiler which meets all the requirements of service and which is so designed as to operate efficiently and satisfactorily under all operating conditions. Obviously, more feeds than one may be connected with each of the pendulum operated valves if desired, although we do not deem this necessary to efficient operation in installations now contemplated, and various other changes and modifications than those specifically referred to are deemed to be within the spirit of the invention and the scope of the following claims.

What we claim is:—

1. A rail and flange oiler including, in combination, a lubricant reservoir of the condensation displacement type, said reservoir provided adjacent to its top with lubricant outlet openings, and a gravity-responsive member arranged within said reservoir and having one end pivotally supported between and adjacent to said outlet openings and provided adjacent to its pivot with valve elements for cooperation with said outlet openings, whereby when said gravity-responsive member hangs axially relatively to said reservoir said openings will be closed by said valve elements and upon relative movement between said member and reservoir one of said valve elements will be unseated and its respective opening opened.

2. A rail and flange oiler including, in combination, a lubricant reservoir of the condensation displacement type, said reservoir provided adjacent to its top with a pair of lubricant outlet openings, and a gravity-responsive member arranged within said reservoir and having one end pivotally supported between and adjacent to said outlet openings and provided adjacent to its pivot with valve elements for cooperation with said pair of outlet openings, whereby when said gravity-responsive member hangs axially relatively to said reservoir both of said openings will be closed by said valve elements and upon relative movement between said member and reservoir one of said valve elements will be unseated and its respective opening opened.

3. A rail and flange oiler including, in combination, a lubricant reservoir provided with lubricant outlet openings, a gravity-responsive member provided with valve elements for cooperation with said outlet openings, whereby when said member is stationary relatively to said reservoir said openings will be closed and upon relative movement between said member and reservoir one of said openings will be opened, and vibration-responsive means associated with said outlet openings for controlling the flow of lubricant therethrough independently of the action of said gravity-responsive member.
4. A rail and flange oiler including, in combination, a lubricant reservoir provided with lubricant outlet openings, a gravity-responsive member provided with valve elements for cooperation with said outlet openings, whereby when said member is stationary relatively to said reservoir said openings will be closed and upon relative movement between said member and reservoir one of said openings will be opened, and vibration-responsive means comprising ball valves associated with said outlet openings for controlling the flow of lubricant therethrough independently of the action of said gravity-responsive member.
5. A rail and flange oiler including, in combination, a lubricant reservoir, provided with a pair of valve-controlled lubricant outlet openings, a pendulum pivoted intermediate said openings and carrying valve actuating elements cooperating with said openings, both of said openings being closed when said pendulum is at rest relatively to said reservoir and one or the other of said openings being opened when said pendulum and reservoir move relatively to each other, and means for damping the action of said pendulum.
6. A rail and flange oiler including, in combination, a lubricant reservoir, provided with a pair of valve-controlled lubricant outlet openings, a pendulum pivoted intermediate said openings and carrying valve actuating elements cooperating with said openings, both of said openings being closed when said pendulum is at rest relatively to said reservoir and one or the other of said openings being opened when said pendulum and reservoir move relatively to each other, and means including dash-pot elements for damping the action of said pendulum.
7. A rail and flange oiler including, in combination, a lubricant reservoir, said lubricant reservoir provided with a valved lubricant outlet openings, a gravity operated member provided with valve actuating elements for controlling said openings, means providing lubricant passages in communication with said openings and through which the lubricant is fed to its points of application, vibration-responsive valve elements controlling said passages, and manually controlled means for varying the rate of flow of the lubricant through said passages.
8. A rail and flange oiler including, in combination, a lubricant reservoir adapted to be mounted upon a railway vehicle, said reservoir provided with a pair of valve-controlled lubricant outlet openings, a pendulum pivoted intermediate said openings and adapted upon tilting of said reservoir to permit flow of lubricant through one or the other of said openings as when said vehicle travels upon a blanked curve, said pendulum operating to close both of said openings when said vehicle is in normal position as upon straight track, means defining passages in communication with said openings and through which the lubricant is fed to points of application, a vibration-responsive valve in each of said passages, each of said vibration-responsive valves being normally seated when the vehicle is at rest but unseated when the vehicle is in motion, and manually controlled valves for controlling the rate of flow of the lubricant through said passages.
9. In a rail and flange oiler, a lubricant reservoir provided with a cap, a pair of passages formed in said cap and affording a means for egress of the lubricant, means including a relatively fixed valve member in each of said passages, and a cooperating valve member movable with respect thereto for controlling the egress of oil from said reservoir, and a gravity-responsive member carrying said latter valve members and adapted to seat both of same when normal to said cap but to unseat one or the other thereof when at an angle to said cap.
10. In a rail and flange oiler, a lubricant reservoir provided with a cap, a pair of passages formed in said cap and affording a means for egress of the lubricant, means including a relatively fixed valve member in each of said passages and a cooperating valve member movable with respect thereto for controlling the egress of oil from said reservoir, and a gravity-responsive member carrying said latter valve members and adapted to seat both of same when normal to said cap but to unseat one or the other thereof when at an angle to said cap, the relatively fixed valve members being adjustable to vary the opening positions of the valves relatively to the angular positions of said gravity-responsive member.
11. In a rail and flange oiler, the combination with a lubricant reservoir having lubricant feed-control valves, of an oscillatory pivoted member controlling the operation of said valves, and means including supplemental guide members associated with the free swinging end of said member for confining its oscillations in a plane normal to its pivot.
12. In a rail and flange oiler, the combination with a lubricant reservoir having lubri-

cant feed-control valves, of an oscillatory pivoted member controlling the operation of said valves, and means associated with said member for confining its oscillations in a plane normal to its pivot and for damping its pivotal action.

13. In a rail and flange oiler, the combination with a lubricant reservoir having lubricant feed-control valves, of an oscillatory pivoted member controlling the operation of said valves, and means associated with said member for confining its oscillations in a plane normal to its pivot and for damping its pivotal action, said means including a cylinder carried by said member and a piston substantially fixed relatively to said member and carried by said reservoir.

14. In a lubricator, a reservoir adapted to contain lubricant under pressure, a valve controlled feed conduit connected with said reservoir, and pressure gages connected with said reservoir and conduit respectively, said gages adapted to show a difference in pressures when the valve of said conduit is closed and a balance of pressures when it is open.

15. A rail and flange oiler for use with a railway locomotive and a train drawn thereby, said rail and flange oiler adapted to supply lubricant to the inside of the outer rail head upon curves and including a reservoir carried by the locomotive and adapted to contain lubricant under pressure and provided with valve controlled feed conduits leading to delivery nozzles arranged adjacent to the wheels at the two sides of a car of said train, three pressure gages mounted in the locomotive cab, one of said gages communicating

with said reservoir and the other gages communicating with the two feed conduits respectively, and means operating to open the valves of said conduits independently but not simultaneously, whereby when said valves are closed the reservoir gage will show a difference in pressure with respect to the other two gages and when either of said valves is open the gage of its respective conduit will show a balance of pressure with the reservoir gage.

16. The combination with a rail and flange oiler including a lubricant reservoir and means associated therewith for feeding lubricant at predetermined times to the wheel flanges of a railway vehicle, of a bracket applied in predetermined fixed relation adjacent to one of such wheels, and a lubricant delivery member including a body portion provided with an attaching lug secured to said bracket, a delivery nozzle adjacent to one end of said body portion and arranged in fixed angular relation to said lug, and means at the other end of said body portion forming a member of a universal coupling for a conduit through which lubricant is fed from said reservoir to said nozzle, the fixed relation of said bracket relatively to said wheel and the angular relation of said nozzle to the lug secured to said bracket determining the point of projection of lubricant from said nozzle upon the flange of said wheel.

In testimony whereof we have hereunto set our hands this 22nd day of January A. D. 1929.

FRANK WILLIAM EDWARDS.
NORMAN M. BARKER.
